PLASTIC NAILING COMPOSITION

Filed June 8, 1929

Inventor:

John A. Wires

By: *Arthur W. Hallow*
Attorney.

UNITED STATES PATENT OFFICE

JOHN A. WIRES, OF CHICAGO, ILLINOIS, ASSIGNOR TO THE NATIONAL KELLASTONE COMPANY, OF CHICAGO, ILLINOIS, A CORPORATION OF DELAWARE

PLASTIC NAILING COMPOSITION

Application filed June 8, 1929. Serial No. 369,385.

This invention relates to improvements in plastic nailing compositions and it consists of matters hereinafter described and more particularly pointed out in the appended claims.

5 The primary object of the invention is to provide a plastic composition which after hardening, will receive the smaller nails or tacks driven thereinto without splitting or cracking.

10 Another object of the invention is to provide a composition which will adhere to cementitious or like surfaces whereby certain covering for said surfaces may be nailed or tacked in place thereon.

15 Still a further object of the invention is to provide a composition of this kind by which a strip may be conveniently formed at the junction of a concrete or like floor and a building wall, which strip will not only seal off

20 the usual draft inducing crevices at this point, but will receive and hold the smaller nails or tacks by which a floor covering such as a carpet may be secured at its margins to said strip to cover said floor.

25 These objects of the invention, as well as others together with the many advantages thereof will more fully appear as I proceed with my specification.

In the drawings:

30 Fig. 1 is a perspective sectional view of the junction of a concrete floor and a building wall, showing in one part thereof a nailing strip made in accordance with my invention and showing in another part thereof the manner in which the nailing strip is produced.

35 Fig. 2 is a detail sectional view through adjacent wall and floor portions with one form of my improved nailing strip in place thereon and having secured thereto, the marginal parts of a carpet and lining therefor.

40 Fig. 3 is a view similar to Fig. 2 showing a slightly modified form of nailing strip for the marginal part of a carpet wherein no lining is employed.

45 Referring now in detail to the ingredients employed in my improved composition which in a plastic state is of about the consistency of a substantially heavy first coat plaster, I employ powdered magnesite and mix the same

50 dry with ordinary wood sawdust. In pro-

portion I employ by weight approximately one and one-half times as much of the magnesite as sawdust; for example, 30 lbs. of magnesite to 20 lbs. of sawdust. I then add there-to about four times as much sand as there is sawdust and by weight I find that 80 lbs. of sand makes a good proportion.

55 To provide a binder for the ingredient thus far set forth when the same is reduced to a plastic state by the addition of a suitable liquid, I add thereto, asbestos fibers in wool form to an extent approximating in weight about one-fourth of that of the sawdust. Thus about 5 lbs. of such asbestos fiber is added to the sawdust, magnesite and sand. These are 60 all thoroughly intermixed together preferably before adding liquid which reduces the mass to plastic form.

65 To reduce the mixed ingredients just above mentioned, to a plastic mass, I add thereto 70 sufficient chloride of magnesium having a specific gravity of about 20° as disclosed by a Baumé hydrometer and thoroughly mix the same with said ingredients until the plastic mass has the consistency of a substantially 75 heavy first coat plaster. In the mass, the sawdust not only acts to give body thereto but acts in conjunction with the asbestos fibers to bind the mass together. Upon hardening 80 the composition will receive nails driven thereinto without cracking and breaking up into chips.

85 My improved composition is especially adopted for use in providing strips upon concrete and like floors to receive tacks or nails by which suitable floor coverings, such as carpets and linoleums may be secured against movement upon such floors.

90 In Fig. 1 I have illustrated the manner in which I form upon a concrete or like floor 1 adjacent a building wall 2, a strip 3 to which a floor covering and any suitable kind may be tacked or nailed. In forming such a nailing strip, I lay a guide strip 4 of wood upon the floor, spaced a suitable distance from and extending parallel with said wall. This wooden guide strip, together with the floor and wall provides a channel or groove 5 which I fill with my improved composition 95 100

while in a plastic state as indicated at 6 in Fig. 1.

Thereafter with a strike off tool 8 having a portion so engaged with the guide strip as 6 to be guided thereby, I strike off the excess composition to leave a strip 9 upon the floor, a part of which engages the wall. Such a strip which is bevelled at 10 on its top surface along that margin spaced from the wall, effectively adheres to the wall and floor upon setting seals up the crevice at the junction of said floor and wall.

In laying a carpet 11 upon the floor, which carpet is of the kind requiring a pad or lining 12, the lining is just laid upon the floor and the carpet is disposed thereon, with the superposed margins thereof covering the nailing strip 9. Thereafter tacks or nails 13 are driven through said margins and into the 20 nailing strip which receives them in the manner of wood.

In Fig. 3 I have shown a nailing strip 9^a for a thicker and heavier carpet 11^a that requires no lining. Under such circumstances, 25 the bevelled surface 10^a is of a lesser angle so that no ridge or wrinkle will appear in the laid carpet where it leaves the strip to engage the floor.

A nailing strip formed from my improved 30 composition is not only fireproof, but seals the usual junction crevice between floor and wall so that no draft can issue through said wall under suction to soil the wall and its finishings, nor can vermin pass from one room to 35 the other through said junction crevice. It adheres quite effectively to a concrete surface and will take all nails and tacks within reason, driven thereinto much in the manner of wood.

40 While in setting forth my invention, I have referred in detail to the ingredients as well as to the proportions thereof and have described the composition as employed as a nailing strip for carpets, the same is to be considered 45 merely as illustrative so that I do not wish to be limited thereto except as may be pointed out in the appended claim.

I claim as my invention:—

46 A composition carpet-tacking strip cementitiously adhered to a nail-impenetrable floor and positioned against the wall, and comprising a set mixture of the reaction products of magnesite and magnesium chloride together with bodying material of saw-dust and sand, 55 said composition sealing the joints between the floor and wall.

In testimony whereof, I have hereunto set my hand, this 4th day of June, 1929.

JOHN A. WIRES.
